UNITED STATES PATENT OFFICE.

MILTON O. GRISWOLD, OF ROCK ISLAND, ILLINOIS, ASSIGNOR TO GRISWOLD MANUFACTURING CO., OF ROCK ISLAND, ILLINOIS, A CORPORATION OF ILLINOIS.

VENDING-MACHINE.

1,131,058.

Specification of Letters Patent.

Patented Mar. 9, 1915.

Application filed January 12, 1914. Serial No. 811,658.

To all whom it may concern:

Be it known that I, MILTON O. GRISWOLD, a citizen of the United States, residing at Rock Island, in the county of Rock Island 5 and State of Illinois, have invented certain new and useful Improvements in Vending Machines, of which the following is a specification.

My invention relates to improvements in vending machines and has particular reference to means of this character embodying a plurality of movable connected receptacles or pockets, preferably in the form of a rotatable carrier or drum, and novel operating mechanism to move or advance the connected receptacles or pockets, to an exposed, removing or discharge position, whereby the articles contained therein will be vended.

An important object of this invention is 20 to provide means of the above mentioned character, which are comparatively simple in construction, inexpensive to manufacture, strong, durable, and not liable to derangements.

25 A further object of the invention is to provide means of the above mentioned character which are convenient and attractive in use.

30 A further object of the invention is to provide operating mechanism, adapted to accurately move or advance the connected receptacles or pockets, preferably in the form of a rotatable carrier or drum, to the precise position, for exposing the article or 35 articles to be vended, whereby the same may be readily removed, such mechanism also serving to positively lock the carrier or drum against improper rotation, before or after such movement or advancement, 40 whereby the article or articles contained in the adjacent preceding or succeeding pockets cannot be fraudulently removed.

45 Other objects and advantages of this invention will be apparent during the course of the following description.

50 In the accompanying drawings forming a part of this specification and in which like numerals are employed to designate like parts throughout the same, Figure 1 is a perspective view of a vending machine embodying my invention, Fig. 2 is an elevation of the inner side of operating mechanism, contained in the invention, Fig. 3 is a plan view of one of the operating mechanisms and its associated carrier or drum, Fig. 4 is

a perspective view of a rotatable head or disk included in the operating mechanism, Fig. 5 is an elevation of the outer side of the same, Fig. 6 is a transverse sectional view, taken on line 6—6 of Fig. 3, Fig. 7 60 is a horizontal sectional view, taken on line 7—7 of Fig. 5, and, Fig. 8 is a perspective view of holding or locking pawls and the casing therefor.

In the drawings, wherein for the purpose 65 of illustration, is shown a preferred embodiment of my invention, the numeral 10 designates a shell or cabinet as a whole, which is attractive in appearance, and preferably of the design shown. The upper portion or 70 end of this shell or cabinet is provided with a longitudinal exposure or delivery opening 11, from or through which the article or articles to be vended are preferably removed by hand. Mounted upon the upper 75 portion of the shell or cabinet 10 is an attractive sign board 12, adapted for the reception of the directions for the use of the machine or advertisements or the like. The forward side of the shell or cabinet 10 is 80 normally closed by a preferably removable door or wall 13, the upper longitudinal edge of which is adapted to be passed between relatively stationary lugs 14, forming with the door a detachable hinge joint, as more 85 clearly shown in Fig. 6. The lower longitudinal edge of the door 13 is adapted to be slidably moved upon a floor or bottom and held in its closed position, by a lock 16 including a bolt 17, adapted for movement 90 into and out of an opening formed through the floor or bottom 15.

Extending longitudinally through approximately the central portion of the shell or cabinet 10 is a preferably horizontal shaft 95 or spindle 18, upon which are independently rotatably mounted carriers or drums 19, which are identical. While these carriers or drums are thus free to rotate upon the shaft or spindle 18, they cannot partake of 100 perceptible longitudinal movements thereof.

As more clearly shown in Figs. 3 and 6, each rotatable carrier or drum comprises circular ends or heads 20, connected by spaced radial longitudinal strips, partitions 105 or elements 21, the outer longitudinal edges of which extend outwardly beyond the peripheries of the heads or ends 20, as clearly illustrated in Fig. 6. These strips or partitions 21 carry at their inner longitudinal 110

edges laterally extending flanges 22, as shown. It is thus seen that each rotatable carrier or drum 19 is provided with a plurality of radial longitudinally extending 5 pockets or receptacles, formed by the partitions 21 and associated elements.

While I prefer to employ the plurality of connected pockets or receptacles in the form of a rotatable carrier or drum, yet I do not 10 wish to, in any way restrict, the invention to such construction, as satisfactory results are obtainable by connecting the pockets or receptacles by other means, such as by an endless belt, or the like. The partitions 22 15 are provided at their outer longitudinal edges with openings 23, which are in alignment, forming an angular groove or recess. Surrounding each carrier or drum is a preferably flexible guard-band 24, arranged 20 within the annular groove or recess formed by the opening 23, as shown. The opposite ends of the guard-band 24 terminate at or adjacent the exposing or delivery opening 19 and are securely attached to the upper 25 portion or end of the shell or cabinet 10, adjacent the longitudinal walls of such opening. The function of this guard-band is to retain the article or articles within the 30 pockets or receptacles of the drum or carrier during the rotation of the same, so that they may be safely carried to the exposing or delivering opening 19.

The numeral 25 designates operating mechanisms as a whole, corresponding in 35 number and arrangement with the rotatable carriers or drums. These operating mechanisms are identical, whereby a detailed description of one will suffice for both. Each operating mechanism is mounted upon the 40 inner side of the door or wall 13, and includes an open or skeleton approximately circular head or disk 26, including a central hub 27, rigidly mounted upon a shaft or spindle 28, as more clearly shown in Figs. 45 4 and 7. As clearly shown in Fig. 7, the rotatable spindle 28 passes through an apertured exterior boss 29, carried by the door or wall 13.

The numeral 30 designates an operating 50 handle, knob or element, which is preferably rigidly and detachably connected with the outer end of the shaft or spindle 28. Rigidly connected with the inner side of the hub 27 are pins or studs 31, carrying preferably circular heads or disks 32, preferably frusto-conical in cross-section and decreasing in diameter outwardly. As clearly 55 shown in Fig. 3, the heads or disks 32 of the operating mechanism, are arranged 60 near, and partly, but not wholly, to one side of the angular groove formed by the openings 23 in the partitions 21. These heads or disks 32 are arranged exteriorly of the guard-band 24, and in such positions with 65 respect to the angular groove formed by the

openings 23, that each of them is successively moved through such angular groove, upon the rotation of the head or disk 26, as will be apparent hereinafter. As clearly shown in Fig. 6, when the heads 32 occupy 70 their normal vertical position, they are arranged within two of the adjacent pockets formed by the partitions 21, whereby they serve to positively lock the rotatable carrier or drum against movement before and 75 after the advancement thereof. It is obvious that when the handle 30 is rotated, for preferably one-half of a revolution, in the direction of the arrow in Fig. 1, the upper head 32 engages the intermediate adjacent 80 partition 21, to advance the rotatable drum or carrier a step, whereby the pocket or receptacle thereof is moved into partial or total registration with the exposing or removing opening 19, the lower head 32 traveling 85 upwardly within and through the angular groove formed by the opening 23 and finally occupying a position in the succeeding upper adjacent pocket, whereby the rotatable carrier or drum is again locked against rotation, the other head remaining in the same 90 pocket, until the carrier or drum is again rotated or moved a step.

Yielding means are provided to oppose the rotation or movement of the heads 32 95 included in each operating mechanism and to return the same to their normal position, comprising horizontal spaced rods 33, arranged upon the inner side of the wall or door 13, and rigidly connected therewith in 100 spaced relation, by a supporting bracket 34.

The numeral 35 designates reciprocatory plates, provided with longitudinal flanges 36, which are apertured to receive the guide rods 33. The inner flanges 36 slidably engage with the pins or studs 31. Connected with the outer flanges 36 are suitably stiff retractile coil springs 37, urging the reciprocatory plates 35 inwardly.

The head or disk 26 is preferably provided at diametrically opposite points and upon their exterior faces, with coin receiving openings or passages 38, within which are arranged spaced check or coin supporting pins 39, adapted to support or hold up 110 a coin of the proper denomination or diameter, such as a nickel, but allowing smaller coins, such as dimes or pennies and slugs of improper sizes, to drop downwardly there-through. The head or disk 26 is provided 115 adjacent each coin receiving recess 38 with slot shoulders 40, 40' and 41, and inwardly of and adjacent the same with stop shoulders 42 and 42', as shown.

The numerals 43 and 44 designate locking 125 elements, fingers or pawls, having their free ends hooked, as shown, and normally arranged respectively between the stop shoulders 40, 40' and 42, 42'. The holding elements or pawls 43 and 44 are arranged with 130

in a casing 45, and pivoted thereto, as shown at 46. The casing 45 is arranged upon the exterior surface of the wall or door 13, as more clearly shown in Figs. 1 and 6, the 5 same being attached thereto by any suitable means. The hooked ends of these holding or locking elements or pawls pass through suitable openings 46' in said door or wall. The locking elements or pawls 43 and 44 are 10 moved or urged toward each other by a suitably stiff retractile coil spring 47, connected therewith by any suitable means. Surrounding that side of the head or disk 26 toward which it is rotated in operation, is a 15 curved coin or check guard 48, connected with attaching elements 49, fixed upon the inner surface of the door or wall 13. The function of the element 48 is to prevent the proper coin, in this instance a nickel, from 20 falling out of the coin receiving recess 38, as the same is rotated downwardly with the head 26. As above stated, the head or disk 26 is rotated one half of a revolution, more or less, to advance the carrier or drum a step, 25 whereby the pocket thereof is moved into registration with the exposing or removing opening. Upon the first part of the turning movement of the head or disk 26, the coin 50, engages the outer or upper holding element 30 or pawl 43, elevating the same, whereby its hooked end will clear the stop shoulders 40 and 41. Upon further turning movement of the head or disk 26 in the same direction, 35 the coin engages the hooked end of the inner or lower locking element or pawl 44, to swing such hooked end downwardly, whereby the same will clear the shoulder 42. The head or disk 26 is now free to be turned for one half of a revolution, more or less, until 40 the hooked ends of the locking elements or pawls 43 and 44 are arranged between the other sets of stop shoulders 40, 41, and 42, 42', at which time the head or disk is again locked against rotation. When thus again 45 locked against rotation, the head or disk 26 is so arranged that the coin within the lower coin recess 38 is still engaged by the coin guard 48, and retained thereby in a position, whereby the same is readily observable from 50 the exterior of the machine, through an opening 51 formed in the wall or door 13, as more clearly shown in Fig. 1. Upon the next turning or rotating of the head or disk 26 for one half of a revolution, more or less, 55 the coin will drop from the lower coin receiving recess 38, and fall upon the bottom or floor 15 of the shell or cabinet.

As is obvious, the inner surface of the wall or door 13 constitutes one wall of the coin 60 receiving opening or recess 38. When an improper coin of too small diameter, such as a penny, dime or the like, pass into the coin receiving recess or opening 38, such coin will not be supported by the pins 39, but will 65 pass therebetween, the same engaging a bev-

eled portion 52, to be deflected thereby through a passage or recess occurring at 53, the coin then passing through an opening 54. After passing through the opening 54 the coin enters an interior coin chute 56, having 70 communication, by means of an opening (not shown) with an exteriorly arranged coin chute 56', serving to return the coin to the operator. The coin is primarily fed to the recess or opening 38 through a coin slot 75 57, of just the proper size to receive a coin of the predetermined denomination or diameter, such as a nickel, and being too small to permit of the insertion of too large a coin, such as a quarter or the like. 80

The operation of the machine is as follows: When it is desired to secure the article or articles within one of the receptacles or pockets of either of the rotatable carriers or drums 19, the coin, of the proper denomination, is 85 inserted into the slot 57 and gravitates into the coin receiving opening or recess 38, to be supported therein by the pins 39. The handle 30 is now turned clockwise for one-half of a revolution, more or less. Upon 90 first turning the handle 30, the head or disk 26 is turned in the same direction, whereby the outer portion of the coin 50 encounters the hooked end of the pawl 43, elevating the same whereby it will clear 95 the stop shoulders 40 and 41. Further turning movement of the head 26 brings the lower portion of the coin in engagement with the hooked end of the pawl 44, swinging the same inwardly so that it will clear 100 the shoulder 42. The movement of the head 26 may now be continued for the rest of the half of the revolution, more or less, such movement being arrested when the other set of stop shoulders are moved into proximity 105 to the pawls 43 and 44, the pawl 43 again being arranged between the stop shoulders 40 and 40' and the pawl 44 between the stop shoulders 42 and 42', whereby the head 26 is positively locked against undue turning 110 movement in both directions. Upon the turning movement of the head 26, as above stated, the heads 32 operate to advance the rotatable drum 19 a step, whereby the succeeding pocket or article holding receptacle 115 is moved into partial or complete registration with the exposing or removing opening 19. In this operation the upper head 32 engages the partition arranged between the heads 32, the same traveling downwardly in such engagement to properly advance the drum, while the lower head 32 travels upwardly within the annular groove or recess formed by the openings 23, such lower head finally assuming the upper position within the succeeding pocket. It is 120 thus seen that the heads 32 and associated elements serve to advance the rotatable drum a step upon each one half of a revolution of the head 26, and also lock such drum 125 130

against rotation in either direction, when the coin controlled means has locked engagement with the head 26. Upon the turning movement of the head 26, the hub 27 is also turned for effecting the movement of the heads 32 carried by the studs 31. These studs are accordingly moved laterally in the arc of a circle, in slidable engagement with the inner flanges 36 of the reciprocatory plates 35, which are thereby made to move outwardly longitudinally of the guide rods 33. This movement of the plates 36 is opposed by the retractile coil springs 37, which together with the plates 36, serve to normally hold the head 26 and associated elements in the proper starting position, whereby the coin will be sure to enter the coin receiving recess 38. When the head 26 has been rotated for one half of a revolution, as above explained, the coin within the recess 38 travels therewith in a downward direction, in slidable engagement with the guard 48, and is prevented thereby from falling out of the opening 38. When the head 26 is again locked against movement, this coin will still remain in the recess 38, which now occupies the lower position, such coin being engaged by the lower end of the guard 48, which overlaps or extends partially across the then lower recess 38. When in this position the coin may be observed from the exterior of the machine through the opening 51. The next time the head 26 is turned for one half of a revolution, more or less, the coin drops from the recess 38 before such recess can reach or move near to the slot 57. When an improper coin is employed, that is one having too small a diameter, such coin will drop through the space between the pins 39, strike against the beveled portion 52, be deflected thereby through the passage or space occurring at 53, pass through the opening 54 in the head 26, through the interior chute 56, and finally into the exterior chute 56', to the operator.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having described my invention, I claim:

- 55 1. A vending machine of the character described, comprising a plurality of movable connected article holding pockets, a pivoted head disposed near and upon one side of the pocket, a pair of spaced members secured to one side of the pivoted head and arranged to be moved into and out of engagement with the walls of the pockets to advance the same and hold them against improper movement, and means to move the pivoted head.
- 60 2. A machine of the character described,

comprising a plurality of movably mounted connected article holding receptacles, a pivotally manually operated operating element arranged near and upon one side of the adjacent receptacles, and a laterally extending member carried by the said element to rotate therewith and have slidable engagement during a portion of its movement with the outer extension of one of the receptacles.

3. A machine of the character described, comprising a plurality of movably mounted connected article holding receptacles having their side walls provided with openings in registration for forming in effect a groove, a rotatable element mounted near the connected receptacles, and a plurality of members carried by the rotatable element and so arranged that when one of them is operating in slidable engagement with the side wall of one receptacle the other is operating within the groove.

4. A machine of the character described, comprising a rotatable drum provided with a plurality of radially arranged partitions affording article holding receptacles therebetween, a manually operated pivoted element arranged near and upon one side of the rotatable drum, and a member carried by the said element and adapted to operate in engagement with the partitions.

5. A machine of the character described, comprising a rotatable drum provided with a plurality of lateral extensions, a rotatable element arranged near and upon one side of the drum, and a member carried by the rotatable element for rotation therewith and arranged to successively engage and disengage the lateral extensions.

6. A machine of the character described, comprising a rotatable carrier provided with a plurality of spaced lateral extensions, a rotatable element mounted near and upon one side of the drum, and a pair of spaced members carried by the rotatable element and arranged for movement into and out of the spaces occurring between the lateral extensions.

7. A machine of the character described, comprising a rotatable carrier provided with laterally extending spaced partitions affording article holding chambers therebetween and provided at their outer edges with openings, a rotatable element arranged near and upon one side of the rotatable carrier, and a pair of spaced members carried by the rotatable element and arranged to pass through said openings into the chambers occurring between the partitions.

8. A machine of the character described, comprising a rotatable carrier provided with laterally extending spaced partitions affording article holding chambers therebetween and provided near their outer edges with openings, a guard-band surrounding the rotatable carrier and arranged within said open-

- ings, a rotatable element arranged near and upon one side of the carrier exteriorly of the guard-band, and a pair of spaced members carried by the rotatable element and arranged to pass through said openings into the chambers occurring between the partitions.
9. A machine of the character described, comprising a movable carrier provided with laterally extending spaced partitions provided near their outer edges with openings, a rotatable head arranged near and upon one side of the carrier, a pair of spaced members carried by the head and arranged to be moved into engagement with the partitions by being passed through the openings, and means to normally hold the head against rotary movement.
10. A machine of the character described, comprising a movable carrier provided with lateral extensions, a rotatable head mounted near the movable carrier, a plurality of members carried by the head and arranged to engage with the lateral extensions, plates arranged upon opposite sides of the members and engaging portions thereof, and yielding means connecting the plates.
11. A machine of the character described, comprising a movable carrier provided with lateral extensions, a rotatable head mounted near the movable carrier, a plurality of members carried by the head and arranged to engage with the lateral extensions, guide rods arranged near the members, reciprocating plates mounted upon the guide rods and having slidable engagement with the members, and retractile coil springs connecting the plates and tending to move them toward each other.
12. A machine of the character described, comprising a rotatable drum provided with radially extending article holding pockets, a head rotatably mounted near and upon one side of the drum to rotate in a plane at approximately a right angle to the plane of rotation of the drum, and a plurality of members secured to the drum to move therewith and arranged for movement into and out of the pockets to engage and disengage with the walls thereof.
13. A machine of the character described, comprising a rotatable carrier provided with spaced lateral extensions, a plurality of headed-studs arranged normally between certain of the lateral extensions and overlapped thereby, and a rotatable head carrying the headed-studs.
14. A machine of the character described, comprising a rotatable carrier provided with spaced lateral extensions, a plurality of spaced members normally arranged between certain of the lateral extensions and partly overlapped thereby, and a rotatable head connected with the members to move the same.
- In testimony whereof I affix my signature in presence of two witnesses.
